UNITED STATES PATENT OFFICE

2,517,281

AWNNG

William G. Brown, Harrisburg, Pa.

Application June 30, 1948, Serial No. 36,140

14 Claims. (Cl. 160—62)

1

This invention relates to awnings and particularly to awnings comprising a plurality of relatively movable vanes or slats.

It is an object of this invention to provide an awning comprising a plurality of relatively movable vanes or slats that may be opened fan-wise or collapsed fan-wise to thus render the awning operative or inoperative.

It is a further object of this invention to provide an awning comprising fan-wise movable vanes capable of being adjusted to extend outwardly from a building opening or outwardly and downwardly therefrom.

It is another object of this invention to provide an awning of the class described having means whereby the vanes are readily and easily movable and yet held against accidental displacement.

It is a further object of this invention to provide an awning of the class described comprising a plurality of groups of fan-wise operable vanes whereby the awning may be collapsed or extended only in part, if so desired.

It is a still further object of this invention to provide an awning of the type described which is simple in construction and operation, economical to manufacture and easily installed.

Further objects and advantages will become apparent as the description proceeds in connection with the accompanying drawings, wherein:

Figure 1 is a top plan view of one embodiment of the awning of this invention showing the vanes in extended position.

Figure 2 is a front elevational view of the awning shown in Figure 1;

Figure 3 is a front elevation similar to that of Figure 2 but with the awning shown in partially collapsed position;

Figure 4 is a vertical sectional view taken substantially along the line 4—4 of Figure 2 with certain parts shown in elevation and other parts omitted;

Figure 5 is a perspective view of the operating cords for the awning of this invention;

Figure 6 is a top plan view of a modification of the present awning;

Figure 7 is a side elevational view of a modified awning construction;

Figure 8 is a perspective view of a still further modified form of awning;

Figure 9 is a perspective view of a modified manner of supporting the individual vanes of the awning of this invention;

Figures 10 and 11 are sketches, in side elevation, of different adjustments of the awning of this invention; and

2

Figures 12 and 13 are perspective views of portions of modifications of the pivotal supports for the guiding means of this invention.

The form of awning shown in Figures 1 to 5 comprises a support or pivot member 1 which may be in the form of a screw threadedly engaged in the upper portion of a window frame 2. The support member 1 may be supported on a window frame or wall of a building in any desired manner and provided with a plastic or other enlarged head or cap. The cap is preferably removable to facilitate assembly of the awning or replacement of vanes. A plurality of similar vanes 3 rounded at their ends, taper toward their rear uppermost ends and are each provided with an opening 4 therethrough adjacent the tapered end. Each of the openings 4 is of larger diameter than the diameter of the shank portion of the support 1 whereby each vane 3 is individually supported by the said support 1 for independent pivotal movement about the axis of the shank of the member 1 and for independent tilting movement relative thereto about any axis transverse to the said shank. The mounting is such that each vane 3 is universally movable about its connection with the supporting means 1. The number of vanes employed will be such that when the awning is open fan-wise to the position of Figures 1 and 11 they will completely cover the generally semi-circular area shown and will still provide for some overlapping at their adjacent edges as clearly indicated in Figure 2. The vanes may be of any desired material such as aluminum wood or plastics.

The vanes described are preferably divided into two groups. One group (shown at the left of Fig. 1) having its rearmost or lowermost vane 5 fixed in some suitable manner (not shown) in position at the rear of the awning structure so that it is incapable of fan-wise movement outwardly. The remaining vanes of the said group are attached, adjacent their free ends, to a flexible strap-like element 6 whereby the separation between the free ends of adjacent vanes of said group is limited substantially as indicated in Figure 1. The strap element 6 may be a fabric web, leather, chain, cord, or any other suitable means to prevent the vanes of the group from separating sufficiently to leave an opening therebetween. The group of vanes shown at the right of Figure 1 are likewise joined by a flexible or other limiting means 7 and the innermost vane 8 of this group is restrained by means (not shown) so that it likewise cannot move outwardly away from the wall of the building. The termi-

nal or end vanes 9 and 10 of the groups described, may thus be manipulated about the supporting means 1 to open or close their respective groups in a fan-wise manner.

A guide structure 11, shown in Figures 3 and 4, has a generally semi-circular rod or tube which is pivoted as at 12 to the wall of the building or other structure on an axis extending generally transverse to the axis of the support 1 and somewhat therebelow. The guide 11 will preferably be made of aluminum tubing since it is light in weight and highly resistant to corrosion; however, any suitable material may be used. An adjusting rod 13 is pivoted to the mid-portion of the guide 11 and extends generally downwardly into a tube-like structure 14 in which it is telescopically received. The tube-like structure 14 is preferably pivoted as at 15 to a window sill or other fixed portion of the building. A wing nut 16 is threaded through one wall of the tube-like structure 14 into frictional engagement with the outer surface of the rod 13 therein whereby the rod 13 may be adjusted longitudinally of the tube-like structure 14 to effect pivotal adjustment of the guide 11 about the axis of the pivot 12. When the vanes of the awning are in the extended position shown in Figure 1, it will be apparent that adjustment of the rod 13 in the element 14 will effect positioning of the guide 11 in such manner that the vanes may assume the positions indicated in Figures 10 or 11 thereby changing the aspects and functioning of the awning to suit varying conditions.

A second semi-circular element 16 is pivoted on an axis 17 parallel to and preferably above the axis 12. The semi-circular structure 16 is preferably of substantially the same size and dimensions as the guide 11 and is provided with an outwardly extending finger 18 at the mid portion thereof. A spring 19 is attached to the free end of the finger 18 and extends to holding means 20 on the element 14. The holding means 20 may be in the form of downwardly directed hooks or may be openings in the element 14 whereby the lowermost end of the spring 19 may be engaged with selected holding means 20 to thereby vary the tension of the said spring. Any suitable manner of attaching the lowermost end of the spring 19 to the structure 14 may be employed, but it is preferred that such means be adjustable to vary the tension in the spring. The spring just described, thus functions to urge the hold-down structure 16 toward the guide 11 and it is contemplated that the free ends of the vanes 3 extend outwardly between the structure 16 and the guide 11. By the arrangement described, means are provided to frictionally engage the vanes and hold them in any desired position of fan-wise adjustment and to also hold the vanes in the desired position against action of wind or the like.

Figure 5 shows only a portion of the awning of this invention, the remaining portions being broken away for clarity of illustration and description. According to the showing of Figure 5, the guide 11 is provided with a pair of pulleys or sheaves 21 and 22 near its mid-portion and sheaves or pulleys 23, 24, 25, 26, 27, 28, 29, 30, 31 and 32 are mounted in fixed relation to the window frame in the general locations shown.

A pair of cords 33 and 34 extend from a cleat or similar holding means 35, on one side of the window frame, upwardly and over the pulleys 25 and 26 respectively. Cord 33 then extends over the pulleys 27, 32 and 22 and has its end attached

to the end portion of the vane 9. The cord 34 extends over the pulleys 26, 23 and 21 and thence to the free end of the vane 10 to which it is attached. By pulling downwardly on both cords 33 and 34 adjacent the cleat 35, the end vanes 9 and 10 of each group will be moved fan-wise outwardly toward each other and toward the position they occupy in Figure 1.

A pair of cords 36 and 37 are similarly trained over the remaining pulleys and have their free ends attached to the ends of the vanes 9 and 10 whereby pulling of the said cords 36 and 37 will effect fan-wise closing movement of the vanes 9 and 10 from the position of Figure 1 to the position shown in Figure 3 or to any position intermediate those two and to a more completely collapsed position than that of Figure 3. The cords 36 and 37 are preferably wound upon a cleat or similar structure 38 as desired. In addition to the manipulations described wherein each pair of cords are manipulated simultaneously, it will be apparent that when the awning is in the position shown in Figures 1 and 2, the operator may, if desired, pull only one of the cords 36 or 37 to thereby close only one of the previously described groups of vanes, leaving the other group fully extended. Any desired combination of manipulations may be resorted to simultaneously or independently to completely or partially open or close either or both of the groups of vanes, all in a manner that will be readily apparent. The operating cords described are not shown in all of the figures of the drawings; they are omitted for clarity of illustration. Clearly, other arrangements of cords or other mechanisms may be employed to operate the described awnings.

Figure 6 illustrates a modified form of awning similar in all respects to that previously described, except that the tubular or rod-like structure 16 and the guide 11 (not shown) are of generally rectangular shape rather than semi-circular and the vanes 3' are of varied lengths whereby they will provide an awning of the generally rectangular shape shown when fully extended.

A further modification is shown in Figure 7 wherein the adjusting rod 13 of Figures 1 to 5 and the tube 14 of those figures is replaced by an adjusting rod 40 pivoted as at 41 to the guide 11 near the mid-portion thereof. The rod 40 extends outwardly beyond the said pivot 41 and has attached thereto the lowermost end of a spring 42 which corresponds to the spring 19 previously described, and performs the same function. Means may be provided to adjust the tension of the spring 42, if desired. From the pivot 41 the rod 40 extends upwardly and rearwardly and is telescopically received within a tubular element 43 pivoted at 44 to the window frame or wall of the building. By means of a wing nut or set screw 45, the distance between the pivots 41 and 44 may be adjusted to thereby position the guide 11 and the hold-down structure 16 in the angular positions shown in Figures 10 or 11 and referred to in connection with Figures 1 to 5. The vanes 3 (only one of which is shown in this figure) extend from the support 1 downwardly over the guide 11 and under the structure 16 in the same manner as the vanes described in connection with Figures 1 to 5. This modification offers the advantage of telescopic adjustment means extending upwardly under the awning and not interfering with a clear view through the window or other opening protected by the awning.

Figure 8 illustrates a still further modification

wherein the guide 11 and hold-down structure 16 are similar to those described previously except that the adjusting means and tensioning spring are located at the lateral extremities thereof rather than at the forward mid-portions as previously described. In this modification, a pair of brackets 50 and 51 support a guide rod 52 generally parallel to the window frame 2. Slidably adjustable on the guide rod 52 is a block 53 having a set screw 54 threaded therethrough whereby the block may be moved to and clamped in any desired position of adjustment along the guide rod 52. A link 55 is pivoted as at 56 to the block 53 and extends upwardly and outwardly to the guide 11 to which it is pivoted at 57 on the inner side thereof. The hold-down structure 16 is provided with a laterally extending finger 58 welded or otherwise rigidly attached thereto. A tension spring 59 extends from adjacent the outermost end of the finger 58 to an adjusting means carried by the block 53. As shown, the spring 59 is attached at its lowermost end to the pin 56 which constitutes the pivot for the link 55. It is contemplated that the adjusting structure and spring just described be duplicated on the opposite side of the awning whereby the guide 11 may be positively adjusted to different positions without flexibility thereof acting to distort the guide. In other words, a link similar to the link 55 will hold the laterally opposite side of the guide 11 in the desired position of adjustment. It will be apparent that upon loosening the set screw 54 and moving the block 53 up or down on the guide rod 52, the link 55 will effect pivotal adjustment of the guide 11 about the axis 12 and the spring 59 will be effective to urge the hold-down structure 16 toward the guide 11. The vanes 3 are indicated in dotted line in this figure and extend downwardly and outwardly from the support 1 and between the members 11 and 16 in the same manner as described previously in connection with other modifications.

Figure 9 illustrates a modified form of support for a plurality of vanes 60. The awning of the present invention may be readily adapted to configurations other than those described and elongated awnings extending a substantial distance along the face of a building may be provided by pivotally supporting vanes 60 on individual pins 61 carried by a bracket or other supporting element 62. It will be apparent that a group of vanes so arranged may be joined at their free ends by flexible limiting straps similar to the straps 6 and 7 described in connection with Figure 1 and that the vanes 60 may be grouped in any desired manner. If desired, the central portion of an elongated awning could be made up of vanes supported in the manner of Figure 9 and at the ends thereof a group of the vanes could be supported on the same pin 61 and moved fan-wise thereto in the same manner as the individual groups of Figure 1.

In all of the modifications described above, it is contemplated that means similar to the guide 11 and the hold-down structure 16 be provided and an arrangement of cords and pulleys similar to that described in connection with Figure 5 is contemplated.

Figure 12 illustrates a modified structure for pivotally supporting a vane supporting and guiding element 70 and an opposed vane hold-down means 71. The guide 70 and the hold-down 71 will preferably be of generally semi-circular construction, similar to that described in connection with Figure 1, but will have their end por-

tions turned inwardly as at 72 and as at 73. The in-turned end portions 72 and 73 are received under bent-up portions 15 and 16 of an attaching plate 74. The plate 74 is attached to the window frame 2 by nails, screws, or the like 77. The opposite ends of the elements 70 and 71 are similarly constructed and pivotally mounted to the other side of the window frame in exactly the same manner as described above. Adjustment of the guide 70 about the axis 72 may be accomplished by any of the means illustrated in Figures 1, 4, 7 or 8, and the hold-down 71 may be urged toward the guide 70 in the manner illustrated in Figures 1, 7, or 8. In all other respects an awning construction in accordance with Figure 12 will be similar to those previously described. This construction offers the advantage of being attachable directly to the window frame and would be desirable in cases where it is inconvenient or impractical to mount the guide and hold-down structures to the walls of the building.

Figure 13 illustrates a further modified form of pivotal mounting for a guide 80 and a hold-down structure 81. The plate 82 may be identical with the plate described in connection with Figure 12 but is so arranged that the open ends of the bent portions 85 are directed inwardly toward the window opening. In this modification the ends of the guide 80 and the hold-down 81 are provided with return bends 86 to properly direct the ends of the said elements into the pockets formed by the portions 85.

It will be clear to those skilled in the art that many modifications besides those specifically described may be resorted to and that other arrangements of cords and pulleys may be provided to effect the desired manipulation of the groups of vanes. Likewise, other forms of adjusting means will be apparent, which adjusting means may replace the means 13, 14 of Figure 4, 40—43 of Figure 7, or 54—57 of Figure 8. Instead of the spring means described for urging the hold-down structure 16 toward the guide 11, it would be clearly feasible to effect the same result with springs coiled around the pivot pins at 17 and acting on the structure 16, or the corresponding element of the other modifications. Such a coiled spring would function in the same manner as a conventional spring hinge. In some instances, springs could be omitted entirely if the element 16 is made sufficiently heavy.

While a limited number of specific embodiments of the invention have been shown and described herein, it is contemplated that other embodiments fall within the scope of the present invention and the invention is to be limited only by the appended claims.

I claim:

1. An awning device comprising a plurality of superimposed vanes individually pivotable about a common axis at one end thereof, means defining said axis mounted on a supporting structure, said plurality of vanes being further pivotable about an axis transverse to said common axis, a guiding structure carried by said supporting structure supporting and guiding the other end of each of said vanes in its pivotal movements about said axis.
2. An awning device comprising a plurality of superimposed vanes individually pivotable about a common axis at one end thereof, means defining said axis mounted on a supporting structure, said plurality of vanes being further pivotable about an axis transverse to said common axis,

a guiding structure carried by said supporting structure supporting and guiding the other end of each of said vanes in its pivotal movements about said axis, said guiding structure being pivotally mounted on said supporting structure on an axis transverse to said common axis.

3. An awning device comprising a plurality of superimposed vanes individually pivotable about a common axis at one end thereof, means defining said axis mounted on a supporting structure, said plurality of vanes being further pivotable about an axis transverse to said common axis, a guiding structure carried by said supporting structure supporting and guiding the other end of each of said vanes in its pivotal movements about said axis, said guiding structure being pivotally mounted on said supporting structure on an axis transverse to said common axis, and additional means bearing on the said other ends of said vanes and urging said vanes into contact with said guiding structure.

4. An awning device comprising a plurality of superimposed vanes, said vanes being mounted for individual universal pivotal movement about adjacent ends whereby said vanes may be pivoted about said ends to open fan-wise, means limiting the relative fan-wise movement of adjacent vanes, means guiding the free ends of said vanes in their fan-wise movement, said guiding means including an element supporting the free ends of said vanes for sliding movement thereover.

5. An awning device comprising a plurality of superimposed vanes, said vanes being mounted for individual universal pivotal movement about adjacent ends whereby said vanes may be pivoted about said ends to open fan-wise, means limiting the relative fan-wise movement of adjacent vanes, means guiding the free ends of said vanes in their fan-wise movement, said guiding means including an element supporting the free ends of said vanes for sliding movement thereover, said element being pivotally mounted on a substantially horizontal axis below the said adjacent ends of said vanes.

6. An awning device comprising a plurality of superimposed vanes, said vanes being mounted for individual universal pivotal movement about adjacent ends whereby said vanes may be pivoted about said ends to open fan-wise, means limiting the relative fan-wise movement of adjacent vanes, means guiding the free ends of said vanes in their fan-wise movement, said guiding means including an element supporting the free ends of said vanes for sliding movement thereover, said element being pivotally mounted on a substantially horizontal axis below the said adjacent ends of said vanes, and a further element over the free ends of said vanes, resilient means urging said further element toward said supporting element whereby to frictionally grip the free ends of said vanes therebetween.

7. An awning device comprising a plurality of superimposed vanes having aligned openings adjacent an end thereof, supporting means passing through said aligned openings, said supporting means being of less diameter than said openings whereby said vanes are independently universally pivotable about said means, means limiting the relative separation between the other ends of adjacent vanes, and means confining the said other ends of said vanes to a predetermined path of movement.

8. An awning device comprising a plurality of superimposed vanes having aligned openings adjacent an end thereof, supporting means pass-

ing through said aligned openings, said supporting means being of less diameter than said openings whereby said vanes are independently universally pivotable about said means, means limiting the relative separation between the other ends of adjacent vanes, means confining the other said ends of said vanes to a predetermined path of movement, the said confining means being pivoted about an axis transverse to said supporting means.

9. An awning device comprising a plurality of superimposed vanes having aligned openings adjacent an end thereof, supporting means passing through said aligned openings, said supporting means being of less diameter than said openings whereby said vanes are independently universally pivotable about said means, means limiting the relative separation between the other ends of adjacent vanes, means confining the said other ends of said vanes to a predetermined path of movement, the said confining means comprising a generally semi-circular guide rod adjustably tiltable about an axis transverse, to and displaced from said supporting means and a second generally semi-circular guide rod tiltable about an axis parallel to said transverse axis, resilient means urging said second guide rod toward said first guide rod, the said other ends of said vanes extending between said guide rods.

10. An awning device comprising a first plurality of superimposed vanes individually pivotable about a common axis at one end thereof, means defining said axis mounted on a supporting structure, said plurality of vanes being further pivotable about an axis transverse to said common axis, a guiding structure carried by said supporting structure supporting and guiding the other end of each of said vanes in its pivotal movements about said axis, a second plurality of superimposed vanes on said common axis and guided by said guiding structure, and means relatively operable to effect movement, either separately or in unison, of said first and second plurality of vanes about said common axis.

11. An awning device comprising at least two sets of superimposed vanes, said vanes being individually universally pivotally movable about adjacent ends whereby said vanes may be pivoted about said ends to open fan-wise, means limiting the relative fan-wise movement of adjacent vanes of each set, means guiding the free ends of said vanes in their fan-wise movement, said guiding means including an element slidably supporting the free ends of said vanes, and means operable to selectively effect opening and closing fan-wise movement of the vanes of each set, said means being further operable to selectively effect said movements of said sets of vanes in unison and individually.

12. An awning device comprising a first group and a second group of superimposed vanes having aligned openings adjacent an end thereof, supporting means passing through said aligned openings, said supporting means being of less diameter than said openings whereby said vanes are independently universally pivotable about said means, means limiting the relative separation between the other ends of said first group of adjacent vanes, and similar means limiting the relative separation of the other ends of the said second group of vanes, means confining the said other ends of said vanes to a predetermined path of movement, separate means for effecting separation of the said other ends of the vanes of each

group, said last-named means being operable either separately or in unison.

13. An awning device comprising separate groups of superimposed vanes having aligned openings adjacent an end thereof, supporting means passing through said aligned openings, said supporting means being of less diameter than said openings whereby said vanes are independently universally pivotable about said means, means limiting the relative said separation between the others ends of the separate groups of adjacent vanes, means confining the said other ends of said vanes to a predetermined path of movement, the said confining means comprising a generally semi-circular guide rod adjustably tiltable about an axis transverse to and displaced from said supporting means and a second generally semi-circular guide rod tilttable about an axis parallel to said transverse axis, resilient means urging said second guide rod toward said first guide rod, the said other end of said vanes extending between said guide rods, an end vane of each of said groups being fixed against pivoted movement about the axis of said supporting means, and independently operable means connected to the vane of each group most remote from said end vanes, said means being operable to effect movement of said vanes in either direc-

5

10

tion along the path defined by said confining means.

14. An awning device comprising a plurality of superimposed vanes individually pivotable about a common axis at one end thereof, means defining said axis mounted on a supporting structure, said plurality of vanes being further pivotable about an axis transverse to said common axis, a guiding structure carried by said supporting structure supporting and guiding the other end of each of said vanes in its pivotal movements about said axis, said guiding structure being pivotally mounted on said supporting structure on an axis transverse to said common axis, and means for holding said guiding structure in selected positions of adjustment about said transverse axis.
